UNITED STATES PATENT OFFICE.

JAMES R. WALSH, OF JACKSONVILLE, FLORIDA.

PLASTER-BOARD.

1,168,131.

Specification of Letters Patent. Patented Jan. 11, 1916.

Application filed December 16, 1914. Serial No. 877,499.

To all whom it may concern:

Be it known that I, JAMES R. WALSH, a citizen of the United States, and a resident of Jacksonville, in the county of Duval and State of Florida, have invented a new and Improved Plaster-Board, of which the following is a full, clear, and exact description.

An object of the invention is to provide a plaster-board formed of folding panels hingedly connected, for folding into compact form, for transportation, and arranged to be extended into the same plane to be applied flat, where no extra stiffness is required, thus eliminating joints between the panels, and eliminating the work of pointing joints, and preventing usual joint marks or cracks on the finish plaster.

A further object of the invention is to provide a plaster-board of hinged sections, arranged to present accordion folds, and collapsible to a greater or less degree, to have a zig-zag form as may be required to present a total effective thickness in accordance with the thickness of the particular wall or partition, or collapsed to a degree to reinforce itself to suit the particular span of a ceiling, or the like.

A further object of the invention is to provide depressions at alternately opposite sides of the plaster-board to receive wall plaster, or to accommodate reinforcing bars, gas pipes, electric conduits, or the like.

A further object of the invention is to provide a plaster-board adapted to be readily cut up into special lengths by the workman to suit his requirements.

Other purposes and advantages of the invention will appear from the specific description following.

Reference is had to the accompanying drawings forming part of this specification, in which similar characters of reference indicate corresponding parts in all the views, and in which:

Figure 1 is a sectional perspective view showing my improved folding plaster-board, and showing one manner in which the board may be applied in flat form; Fig. 2 is a sectional perspective view showing an improved plaster-board having its panels disposed in zig-zag form; Fig. 3 is a perspective view of a plaster-board with certain of the panels in the form of the folds in close relation, and other panels partially extend-

ed; Fig. 4 is a fragmentary horizontal section of a solid plaster wall having my improved plaster-board incorporated therein in zig-zag form.

In carrying out my invention, a series of 60 separate panels, designated generally by the numeral 10, are provided, which may in practice have a width to constitute slats. The bodies 11 of the panels are formed of gypsum, or like plaster-board material. 65 Over each face of the panel is applied a covering of laminated paper 12, of the character generally employed on plaster-boards of ordinary form. The paper covering 12 extends across the respective panels, uniting 70 the same into a continuous sheet, and in a way to constitute hinge joints between the respective panels. The hinge connections constitute accordion joints, so that the panels may be folded into close relation, as indicated at the lower portion of Fig. 3, or a sheet may be extended or collapsed to a greater or less degree, to assume a zig-zag form. To effect the accordion folding of the panels, the bodies 11 are formed with 75 longitudinal recesses 13 at the longitudinal edges, there being one recess at each side edge of a panel, and the respective recesses of a panel being at opposite sides. The paper covering follows the recessed form of the 80 bodies 11, at the joints, so that at each joint a longitudinal groove 14 is produced, the said grooves being alternately in opposite faces of the sheet. At the back of each recess the material of the body 11 and paper 85 covering 10 extends without depression over the joint. The result is that the panels constituting the plaster-board may assume accordion folds. When the folds are in close relation the board is convenient for handling and transportation, and may be sawed 90 into a particular length to suit the requirements of particular work. Similarly, the board may be applied in full size or in fractional sheets to suit particular requirements. 95

The boards in flat form may be applied vertically or horizontally; I have shown in Fig. 1 one application in flat form, the panels in this figure running horizontally. The continuity of the paneled sheet or board 105 eliminates joints, thereby eliminating the work of pointing joints, and preventing the usual joint marks or cracks in the finish plaster. To secure the panels, they may be bedded in cement, or may be nailed or se- 110

cured by wire, according to the particular situation in which the plaster-board is employed.

With a plaster-board constructed as described, the panels may be collapsed to a greater or less extent to give the necessary rigidity in a particular situation, in accordance, for instance, with the thickness of the wall, or the stiffness required in a particular 10 situation, or to suit a given span. It can be applied to beamed and other ceilings, and is particularly advantageous in the construction of vaulted ceilings. It may be employed in solid partitions, and collapsed to a degree 15 to give the desired effective thickness in accordance with the thickness of the wall, while at the same time the partially collapsed panels will present depressions alternately at opposite sides of the board to receive plaster, or gas pipes, or electric conduits to be buried in the plaster, or the depressions may receive reinforcement elements where stiffening bars are required for 20 very high or thin partitions. I have shown 25 the improved bar in Figs. 2 and 4 employed partially collapsed into zig-zag form, thereby presenting depressions at alternately opposite sides, which is filled in with plaster 10. The depressions also provide for receiving a pipe or conduit 20, or a stiffening element. In the zig-zag form the plaster-board may be nailed or wired in place, or may be bedded at the bottom in cement mortar. I employ cleats 16, one form of which 30 is shown in Figs. 2 and 4. These cleats 16 comprise a base member having upwardly projecting studs 17 positioned against adjacent panels 10. The cleats may be secured by any suitable fastener 18, such as a nail 35 or screw.

Having thus described my invention, what I claim as new and desire to secure by Letters Patent, is:

1. A plaster-board consisting of separate 45 plaster-board panels, and a flexible covering at each side thereof hingedly connecting the panels, the said covering forming the only connection between the panels, said panels having recesses extending longitudinally 50 thereof at the joints at alternately opposite faces of the board, the opposed recesses of adjacent panels forming grooves and there being at each joint an ungrooved surface, opposite each groove, the said panels being 55 foldable flat against one another into zig-zag form.

2. A plaster-board formed of separate

plaster-board panels, and flexible material hingedly joining the several panels at both sides, the said plaster panels having recesses 60 at the joints at alternately opposite faces, and the said flexible material being depressed at the joints to correspond with the recesses in the juxtaposed edges of the panels, presenting longitudinal grooves in 65 the board at the joints at alternately opposite sides of the board, alternate joints being plain and ungrooved opposite to the grooves, and the panels being foldable flat onto one another in zig-zag form. 70

3. A plaster-board formed of separate plaster-board panels, and means hingedly joining the said panels together, said board having at each of the joints, a longitudinal groove and a plain, ungrooved surface, the 75 grooves and ungrooved surfaces being reversely disposed at alternate joints to permit a zig-zag folding of the panels.

4. A plaster-board comprising separate 80 plaster board panels, there being a covering of flexible material on both faces hingedly connecting the said panels, adjacent panels being foldable on their said hinged connection through angles to lie close together or to dispose the panels into various angular positions. 85

5. A wall having therein a plaster-board, composed of a series of separate plaster-board panels hingedly connected together and disposed at angles to each other in zig- 90 zag form, presenting depressions at alternately opposite sides between the salient angles of the board, the depressions being defined by adjacent angularly disposed panels, and plaster filling said depressions 95 of the board.

6. A wall having therein a plaster board composed of separate plaster board panels hingedly connected together in zig-zag form 100 presenting at alternately opposite sides depressions between the salient angles of the board, the depressions being defined by adjacent angularly disposed panels, means engaging adjacent panels near the joints and retaining the panels at a given angle to each 10: other, and plaster material filling said depressions of the board.

In testimony whereof I have signed my name to this specification in the presence of two subscribing witnesses.

JAMES R. WALSH.
